UNITED STATES PATENT OFFICE.

WILLIAM S. S. RODGERS, OF COLUMBUS, OHIO.

WRINGER-SUPPORT FOR WASHING-MACHINES.

No. 840,161.

Specification of Letters Patent.

Patented Jan. 1, 1907.

Application filed May 11, 1905. Serial No. 259,855.

To all whom it may concern:

Be it known that I, WILLIAM S. S. RODGERS, a citizen of the United States, residing at Columbus, in the county of Franklin and State of Ohio, have invented certain new and useful Improvements in Wringer-Supports for Washing-Machines, of which the following is a specification.

My invention relates to a new and useful improvement in wringer-supports for washing-machines.

The object of the invention is to provide a suitable support whereby the wringer may be swung and held over the tub of the washing-machine and also whereby the wringer may be readily swung away from the tub.

Another feature resides in the construction of the support whereby it may be mounted on a stand between the tub of the washing-machine and the rinsing-tub so as to be swung over either.

Finally, the object of the invention is to provide a device of the character described that will be strong, durable, and efficient, simple and comparatively inexpensive to make, and one in which the several parts will not be liable to get out of working order.

With the above and other objects in view the invention consists of the novel details of construction and operation, a preferable embodiment of which is described in the specification and illustrated in the accompanying drawings, wherein—

Figure 1 is a side elevation of a washing-machine and its stand, showing the rinsing-tub in dotted lines and illustrating my improved wringer-support arranged on the stand. Fig. 2 is a transverse vertical sectional view taken on the line *x x* of Fig. 1, showing the wringer-support and washing-machine tub in elevation; and Fig. 3 is a transverse vertical sectional view taken on the line *y y* of Fig. 1.

In the drawings the numeral 1 designates a suitable washing-machine stand, on which is arranged a suitable washing-machine tub 2. The stand comprises at its central portion vertical legs 3, which support on their outer sides pivot-pins 4 near their upper ends. On these pins 4 are pivotally supported the side bars 5 of the wringer-support. These side bars are preferably formed of angle-iron, as illustrated in Figs. 2 and 3, and extend at an angle to plate-like portions 6, through which the pivot-pins 4 pass. Short stop-pieces 7 extend downwardly at right angles to the

plate portions 6, and segmental flat guide-pieces 8 extend from the lower ends of the stop-pieces 7 upwardly to the side bars 5 of the wringer-supports, the said pieces 8 extending in the arcs of circles having their centers in the pins 4. On the sides of the stand 1 guide-loops 9 are secured so that the segmental pieces 8 will swing therethrough. Set-screws 10, threaded through the sides of the guide-loops 9, impinge the pieces 8 and when tightened will lock the same in place. In this manner the wringer-support may be rigidly fastened in position. At their upper ends the side bars 5 are bent slightly upwardly and support a wringer board or rest 11, as clearly shown in Fig. 2. This wringer-rest 11 is arranged at such a point as to freely clear the edge of the tub when the side bars are swung and when the side bars are swung toward the tub 2 to rest on the tub, thus being rigidly supported. The usual wringer 12 is mounted on the rest 11, and it will be apparent by observing Fig. 1 that when the rest is swung over the tub the wringer will be supported some distance inward from the outer edge of the tub, thus causing the water wrung from the washing to drip back into the tub, thus keeping the stand and the surrounding floor in a comparatively dry state. The stop-pieces 7, like the side bars 5, being composed of angle-iron, will impinge the central legs 3 when the support is swung over the tub 2, and thus limit the movement of the same, as clearly shown in Fig. 1.

In Fig. 1 I have indicated in dotted lines a rinsing-tub 14 mounted on the stand to the left of the tub 2. Each of the central legs 3 is inclined at its upper end, as at 15, so as to allow the wringer-support to be swung to the left to bring the wringer-rest 11 over the rinsing-tub, the said inclined portions 15 also acting as stops against which the angle-bars 5 abut.

It is apparent that the support may be swung to either side and securely locked in position by the set-screws 10 and also that it may be locked in any intermediate position between the positions shown in Fig. 1, as when it is not in use it may be desirable to have the wringer-support stand between the tubs, so as not to interfere with either of the same.

I wish it understood that the more essential feature of my invention is the arrangement and construction of the wringer support and rest, whereby the wringer may be

swung over the tub, so as to cause the water dripping from the wringer to be entirely caught in the tub, also the provision whereby the wringer may be readily swung to and away from the tub and locked in position.

Having now fully described my invention, what I claim, and desire to secure by Letters Patent, is—

1. The combination with a stand, of a wringer-support pivotally mounted on the stand comprising side bars carrying a wringer-rest at their upper ends, stop-pieces projecting downwardly from the said bars and adapted to engage the stand, guide-pieces extending upwardly from the stop-pieces to the side bars, and means mounted on the stand and associated with the guide-pieces for fastening the wringer-support in place.
2. The combination with a stand, of a

wringer-support pivotally mounted on the stand, the said support comprising side bars and stop-pieces comprising laterally-extending portions, a wringer-rest carried by the side bars at their upper ends, segmental pieces extending from the side bars to the stop-pieces, the said laterally-extending portions of said side bars and stop-pieces adapted to contact with the stand to limit the swinging movement of the support, and means carried by the stand and engaging with the segmental pieces for fastening the wringer-support in position.

In testimony whereof I affix my signature in presence of two witnesses.

WILLIAM S. S. RODGERS.
